UNITED STATES PATENT OFFICE.

JOHN W. KINCAID, OF COVINGTON, KENTUCKY.

MECHANICAL STOKER.

SPECIFICATION forming part of Letters Patent No. 691,391, dated January 21, 1902.

Application filed January 28, 1901. Serial No. 44,974. (No model.)

To all whom it may concern:

Be it known that I, JOHN W. KINCAID, a citizen of the United States of America, and a resident of Covington, in the county of Kenton 5 and State of Kentucky, have invented certain new and useful Improvements in Mechanical Stokers, of which the following is a specification.

The object of my invention is a mechanical 10 stoker especially adapted for locomotive-engines, which throws the fuel upon top of the fire by the forward strokes of a plunger, in which these strokes are varied automatically in rapidity, so as to throw the fuel to all parts 15 of the furnace, in which the relative speeds of the strokes may be changed at will without stopping the machine, in which the backward or return stroke of the plunger is independent of the forward stroke, and in which the 20 operative parts are simple and compact. This object is attained by the means described in the annexed specification and illustrated in the accompanying drawings, in which—

Figure 1 is a side elevation of a mechanical 25 stoker embodying my invention, the trough being shown in section. Fig. 1' is a detail side elevation, upon an enlarged scale, of the rear end of the main-engine cylinder and the secondary engine, the hopper being shown in 30 longitudinal section. Fig. 2 is a rear end elevation of the stoker, part of the hopper being broken off to economize space. Fig. 3 is a detail sectional view of the end of the main cylinder and the piston, showing the ports for 35 admitting steam to and exhausting it from the cylinder, so as to cushion the return stroke of the piston. Fig. 4 is a detail view, upon an enlarged scale, in rear end elevation, of the main-engine cylinder with the cylinder-head 40 removed therefrom and in transverse section of the steam-chest of said main cylinder upon line $y-y$ of Fig. 1'. Fig. 5 is a detail horizontal sectional view of the steam-chest of the main engine, taken upon line $x-x$ of Fig. 4, a 45 part of the conveyer-shaft bearing the cams for operating the valves in the chest being shown in plan. Fig. 6 is a detail perspective view of one of the valves. Fig. 7 is a detail plan view of the valve-seat of the steam-chest 50 of the main engine. Fig. 8 is a detail end view of one of the cams for operating the valve

in the steam-chest of the main engine, the dotted lines showing the relative position upon the shaft of the similar cams. Fig. 9 is a transverse vertical sectional view of the secondary engine, upon an enlarged scale, taken upon irregular line $z-z$ of Fig. 1'. Fig. 10 is a perspective view of the valve of the steam-chamber of the secondary engine. Fig. 11 is a perspective view of the valve which controls 60 the admission and exhaust of steam to and from the secondary engine.

Referring to the parts, the fuel is kept in a hopper A, in the bottom of which are two spiral conveyers $a-a'$ to keep the fuel fed forward to the front of the hopper. Beneath the hopper is the cylinder B of the main engine. Leading from the cylinder into the furnace above the grate-bars is a trough b, within which a plunger b' is reciprocated by piston b^2 of the main engine, the plunger and the piston being directly connected by a rod b^3 . Attached to the forward end of trough b is a cone-shaped deflector d^3 for spreading the coal. Attached to the plunger is an apron b^4 , which reciprocates in a way between the hopper and the cylinder and allows the coal to drop from an opening in the bottom of the forward end of the hopper into the trough in front of the plunger when it is retracted. 80

Spiral conveyers $a-a'$ are rotated by vertical piston-rod c of the secondary engine, whose piston c' is reciprocated in a vertical cylinder C by steam from the boiler admitted to steam-chamber c^2 of secondary engine through pipe c^3 . Valve-seat of steam-chamber c^2 has three ports c^4 , c^5 , and c^6 , c^4 and c^5 communicating through channels c^7 and c^8 with the opposite ends of horizontal valve-chamber c^9 , and c^6 communicating through channel c^{10} (shown 90 in dotted lines) with the general exhaust-channel b^5 , as shown in dotted line, Fig. 1'. 85

The opening of the ports c^4 and c^5 alternately one to the live steam and the other to the exhaust is controlled by valve c^{11} , which 95 is reciprocated vertically by vertical stem c^{12} , which extends upward and has two collars, which are alternately engaged by lugs c^{13} , projecting rearwardly from piston-rod c of the secondary engine. Valve c^{11} has two live-steam holes c^{14} and c^{15} and an S-shaped exhaust-cavity, which puts one of the ports c^4 100

5 c^5 in communication with exhaust c^{10} when the other is in communication with the live steam through either hole c^{14} or c^{15} .

Within chamber c^9 are two pistons c^{16} and c^{17} , connected by a rod c^{18} , which reciprocates valve c^{19} upon its seat. Within chamber c^9 the space between pistons c^{16} and c^{17} is always in open communication with the live steam in chamber c^2 through channel c^{20} . Thus the valve puts channels c^{21} and c^{22} , one of which leads to the top and the other of which to the bottom of secondary cylinder C, alternately in communication with the live steam and with exhaust-channel b^5 through cavity c^{23} in its face to reciprocate piston c' .

15 Piston c' carries at its upper end a head c^{24} , into which fit the ends of links a^2 a^3 , which at their other ends are journaled upon the ends of conveyer-shafts a a' and carry pawls a^4 a^5 , (shown in dotted lines, Fig. 2,) which engage ratchet-wheels a^6 a^7 , secured upon the ends of the conveyer-shafts, so that as the piston-rod c descends an intermittent rotation is imparted thereby to the conveyer-shafts.

20 25 Head B' of the main cylinder is formed integral with the walls of steam-chambers c^2 and c^9 and the head of cylinder C, and the cores for piston-rod c , valve-stem c^{12} , channels c^7 and c^8 , and exhaust b^5 are formed in 30 the intervening metal.

35 Steam-chest or valve-chamber B^2 of the main engine is formed integral with main cylinder B. Valve-seat b^6 has four ports b^7 , b^8 , b^9 , and b^{10} in longitudinal alinement, and two 40 ports b^{11} and b^{12} in transverse alinement with b^{10} . Ports b^7 , b^8 , b^9 , and b^{10} each have a channel b^{13} leading down into a common horizontal core b^{14} , which communicates by channel b^{15} with the rear end of the main cylinder at 45 a distance from the end equal to the thickness of piston b^2 , so that when the piston is at the rear end of its stroke it covers the large port of channel b^{15} into the cylinder. Channel b^{15} has a reduced auxiliary channel b^{16} running back to the rear end of the main cylinder, so that on the return stroke after exhaust through the main channel has been cut off by piston b^2 the steam may exhaust less rapidly than theretofore through the reduced 50 channel, and thereby form a cushion for the rear head of the cylinder. The size of auxiliary channel may be regulated from the exterior by means of a choke-plug b^{40} . Channels b^{13} where they enter core b^{14} each form a seat b^{17} for horizontal choke-plugs b^{18} , which have a screw-threaded connection in the opposite wall of the core and terminate upon the exterior thereof in keys b^{19} , b^{20} , b^{21} , and b^{22} , whereby by turning said keys in one direction 55 or the other the size of each of the channels may be regulated for the admission of greater or less steam to the rear end of the cylinder to vary the rapidity of the forward strokes of piston b^2 .

60 65 Port b^{12} is connected by channel b^{23} with the forward end of cylinder B, the channel forming a main and an auxiliary port leading into

the cylinder to cushion the front head of the cylinder in a manner similar to the rear head, as aforescribed.

70 Port b^{11} is put into communication with main exhaust-channel b^5 by channel b^{24} .

75 Ports b^7 , b^8 , and b^9 are opened to and closed off from live steam which enters the top of valve-chamber through pipe b^{25} by plain valves b^{26} , which are operated by horizontal valve-stems b^{27} , while ports b^{10} and b^{12} are put alternately into communication with exhaust-port b^{11} by valve b^{28} , which is operated by horizontal valve-stem b^{29} and has an exhaust-cavity b^{30} in its face for connecting ports b^{10} and b^{12} with exhaust b^{11} . Valve-stems b^{27} and b^{29} extend through the wall of one side of the valve-chamber and are held by springs b^{31} normally in contact with arms b^{32} , which are journaled upon a horizontal shaft b^{33} , which is supported between brackets b^{34} upon the side of the valve-chamber. These arms b^{32} are each held in contact with cams b^{35} , b^{36} , b^{37} , and b^{38} upon conveyer-shaft a' . Cams b^{35} , b^{36} , and b^{37} have 85 each a single notch and are mounted upon the shaft so that these notches come at one hundred and twenty degrees apart, as shown in dotted line, Fig. 8, while cam b^{38} , which operates valve b^{28} , has three of these notches 90 and is mounted on the shaft so that they come in the same relative position upon the shaft as the three notches upon the other cams.

95 In operation, steam having been admitted to chambers B^2 and c^2 , stem c is reciprocated vertically by secondary engine C, thereby rotating conveyer-shafts a and a' . Conveyer-shaft a' operates valves b^{26} and b^{28} to reciprocate piston b^2 and plunger b' . The steam to the rear end of the cylinder is admitted 100 first, say, through port b^7 , then b^8 , and then b^9 , and the amount may be made to be in an increasing ratio by setting of the choke-plugs b^{18} so that the first forward stroke may be slow, the third very rapid, and the second intermediate. While steam is being admitted 105 through either of ports b^7 , b^8 , or b^9 to the rear end of cylinder the forward is exhausting through port b^{12} and cavity b^{30} in valve b^{28} , and while steam is being admitted through 110 port b^{12} and channel b^{23} to the forward end of the cylinder the rear end is exhausting through port b^{10} . The lap of valve b^{28} upon the side of port b^{10} is made large, as shown in Fig. 4, so that live steam never enters through 115 that port, but it acts simply as an exhaust-port. As the plunger approaches the forward end of the trough a swinging door D is opened in advance of it by an arm d and again falls to its normal position when the 120 plunger is retracted to prevent cold air rushing into the furnace, an effect in which it is assisted by a hood d' , extending over the top of the trough from the hopper to the furnace. Should the coal be thrown too much in one 125 place, the relative speeds of the forward strokes could be changed by means of the choke-plugs without stopping the running of the machine. The speed of the return stroke

of the plunger is entirely independent of the forward strokes and may itself be regulated by means of choke-plug b^{18} by turning key b^{22} to vary size of the exhaust-channel.

5. What I claim is—

1. In a mechanical stoker, a plunger for throwing fuel into a furnace, an engine for reciprocating the plunger, means for automatically varying the speeds of the forward strokes of the plunger, and means for regulating the speed of the forward strokes of the plunger independently of each other, substantially as shown and described.

2. In a mechanical stoker a plunger for throwing fuel into a furnace an engine for reciprocating the plunger, means for automatically varying the speeds of the forward strokes of the plunger, and means for regulating the speed of the forward strokes of the plunger independently of each other without stopping the running of the machine.

3. In a mechanical stoker a plunger for throwing fuel into a furnace, a steam-engine for reciprocating the plunger, a valve-chamber, a series of ports in the chamber leading into a common channel from which steam is admitted to the engine for the forward stroke of the plunger, independent valves for each of said ports except one, a single port for admitting steam to the engine to retract the plunger, an exhaust-port, a valve for putting the said one of the series of ports and said single port alternately into communication with the exhaust and the single port into communication with the live steam to retract the plunger after each forward stroke, and means for actuating each of said valves, substantially as shown and described.

4. In a mechanical stoker a plunger for throwing fuel into a furnace, a steam-engine for reciprocating the plunger, a valve-chamber, a series of ports in the chamber, a common channel from which steam is admitted to the engine for the forward stroke, channels leading from said ports into said common channel, choke-plugs seated in each of said channels for varying their size, independent valves for each of said ports except one, a single port for admitting steam to the engine to retract the plunger, an exhaust-port, a valve for putting the said one of the series of ports and said single port alternately into communication with the exhaust and the single port into communication with the live steam to retract the plunger after each forward stroke, and means for actuating each

of said valves, substantially as shown and described.

5. In a mechanical stoker a reciprocating plunger for throwing fuel into a furnace, a steam-cylinder, a thick piston reciprocating in the cylinder, means for connecting the plunger and the piston, a valve-chamber, a main channel leading from the chamber into the cylinder at a distance from the end slightly less than the thickness of the piston, and a reduced channel running backward from the main channel into the end of the cylinder, whereby the return stroke of the piston is cushioned, substantially as shown and described.

6. In a mechanical stoker a reciprocating plunger for throwing fuel into a furnace, a steam-cylinder, a thick piston reciprocating in the cylinder, means for connecting the plunger and the piston, a valve-chamber, a main channel leading from the chamber into the cylinder at a distance from the end slightly less than the thickness of the piston, a reduced channel running backward from the main channel into the end of the cylinder, and a choke-plug for regulating the size of the reduced channel whereby the return stroke of the piston is cushioned as much as may be desired, substantially as shown and described.

7. In a mechanical stoker the combination of a reciprocating plunger for throwing fuel into a furnace, a steam-engine for reciprocating the plunger, means for automatically varying the speeds of the forward strokes of the plunger, means for varying the ratio of the forward stroke and of the return stroke of the plunger independently of the forward stroke, substantially as shown and described.

8. In a mechanical stoker the combination of a reciprocating plunger for feeding fuel into a furnace, an engine for reciprocating the plunger, a rotating conveyer for feeding the fuel forward to fall in front of the retracted plunger, means for rotating the conveyer, a valve-chamber for the main engine, reciprocating valves in the chamber for admitting and exhausting steam to and from the main engine, and cams mounted upon the conveyer-shaft for reciprocating the valves, substantially as shown and described.
